A. LINDE

TROLLEY WIRE HOLDER FOR ELECTRIC TRAMWAYS AND OTHER RAILWAYS

Filed Sept. 3, 1926

FIG. 3.

FIG. 1.

FIG. 2.

FIG. 4.

FIG. 5.

FIG. 5.

Inventor:

August Linde

UNITED STATES PATENT OFFICE.

AUGUST LINDE, OF MUCKENBERG, NIEDER-LAUSITZ, GERMANY.

TROLLEY-WIRE HOLDER FOR ELECTRIC TRAMWAYS AND OTHER RAILWAYS.

Application filed September 3, 1926, Serial No. 133,470, and in Germany March 20, 1925.

The overhead trolley wire suspension clips now in use are either so arranged that the jaws or cheeks serving to hold the wire are connected with each other by means of 5 screws and the wire is held tight in position by tightening up the screws, or else the clips are made in the form of pincers which are closed and opened by means of oblique surfaces and a central screw arrangement. There are, however, also types which engage with the wire by means of hooks and eyes and are held closed by means of wedges, and finally also types which grip the wire by means of spring-like claws and 10 are secured in position by means of a splint.

In the case of the clips provided with screws, these latter easily get rusted in or else they work loose by the impact of the runners or pulleys and the threads become 20 stripped so that in most cases the clips can only be removed by breaking them so that they are of no further use. Other clips are too heavy and expensive and are not vibration or shock proof. With those having 25 spring-like claws, vital points are the hardness and strength or tempering of the spring devices, as otherwise breakages and consequent falling of the wire can easily occur.

30 In order to avoid these drawbacks the improved wire suspension holder according to the present invention is made without screws, wedges or springs. The two principal parts of the improved holder are, according to the 35 invention pushed into each other by means of a round fillet or tongue and a round groove and into grooves in the wire thus holding the latter tight and in this position are secured by means of a pin passing longitudinally through the holder and fash- 40 ioned at the ends like a split-pin.

The holder according to the invention is illustrated in the accompanying drawings, in which:—

45 Figure 1 is a longitudinal elevation of the holder for one wire;

Figure 2 is an end elevation thereof with a round fillet upon the main part;

50 Figure 3 is an end with a round fillet on the jaw or cheek forming the other part;

Figure 4 is a plan of Figure 1;

Figure 5 is a longitudinal elevation of the suspension holder for two wires;

Figure 6 is an end view thereof;

55 Figure 7 is an end view of another form of holder;

Figure 8 is a front elevation thereof and Figure 9 is an elevation of that part thereof provided with the round tongue or fillet.

The main part or cheek 1 (Figure 1) of 60 the holder has at the top an eye 2 with an internal screw thread 3 for engagement by the suspension bolt (not shown). The cheek 1 is provided with the recesses 4 and 5 and also with the round tongue 6, (Figure 2) 65 all of which extend longitudinally of the holder and with it there is engaged the holding member or jaw 7 provided with the longitudinal recesses 8, 9 and 10 of which the recess 9 fits snugly upon the round 70 tongue 6 of the cheek 1, whilst the recesses 8 and 10 in conjunction with the recesses 4 and 5 of the cheek form at the top a continuous cylindrical hole for the safety pin 11 and below for holding jaws 12 for the 75 rib 13 of the wire 14. The pin 11, intended to prevent any displacement in relation to each other of the cheek 1 and the jaw 7 when engaged with the wire 13, 14, is provided on one end with a head 15, and on the other end projecting from the holder with a slot 16. The two prongs of the slotted end are bent apart like a split pin for the purpose of securing the pin against 80 disengagement and to ensure no displacement of the cheek and jaw in relation to each other. In Figure 1 only half of the 85 jaw 7 is shown, so that the recesses 4 and 5 and also the round tongue 6 of the cheek 1 can be clearly seen.

The construction of the holder according to Figure 3 differs from that according to Figures 1, 2 and 4 merely in the fact that here the round tongue 6¹ is located on the jaw 7¹ whilst the cheek 1¹ is provided with the recess 9¹.

The manipulation and method of operation forms of holders illustrated is precisely the same.

The holder according to Figures 5 and 6 100 serves to carry two wires 18 and 19. The central part 20 possesses at the top the eye 21 with internal screw thread 22. Upon the webs 23 there is provided the cheek 24 which is furnished on each side with a round tongue 25 and two recesses 26 and 27. Upon each side of the cheek engages a jaw 28 provided with the recesses 29, 30 and 31 so that with the recesses 26 and 27 of the central cheek 24 there are formed on each side 105 a cylindrical hole 32 at the top which receives the pin 34 and below a jaw 33 which 110

- holds the wire 18 or 19. The pins 34 are slotted at one end and after insertion the prongs are bent outwards, as already described for the single wire suspension clip.
- 5 Here again also the two round tongues 25 can be provided upon the jaws 28 instead of upon the central cheek 24. In the latter event the cheek 24 would then be provided with two corresponding recesses.
- 10 In Figures 7, 8 and 9 there is shown a further modified form of holder according to the invention, consisting of two plates 35, 36, of which the cheek 35 engages by means of a pin 37 in a slot in the jaw 36.
- 15 The cheek 35 possesses two recesses 38 and 39 and the round fillet 40, and the jaw 36 three recesses 41, 42 and 43 which as previously described when the parts are placed together form at the top a cylindrical hole
- 20 and below the holders, the parts being held together by means of a pin 44 split at one end as already described.
- What I claim and desire to secure by Letters Patent of the United States is:—
- 25 1. A trolley wire suspension holder for tramways and railways comprising a cheek member provided with a threaded eye to permit the cheek member to be suspended, a jaw member, a round fillet on one of said
- 30 members extending longitudinally thereof and a corresponding recess on the other member fitting said fillet whereby the jaw member may be displaced longitudinally of the cheek member, cooperating recesses on
- 35 said cheek and jaw members, and a remov-

able split pin inserted in said last-mentioned recesses to prevent longitudinal displacement between the cheek member and the jaw member.

2. A trolley wire suspension holder for 40 tramways and railways comprising a cheek provided on each side with recesses and a round fillet, a jaw on each side of the cheek and provided with recesses cooperating with the recesses in the cheek and a recess adapted 45 to receive the corresponding fillet when the parts are placed together, and a pin adapted to be secured in the hole formed by each pair of said cooperating recesses to hold the jaws and the cheek together against longitudinal displacement.

3. A trolley wire suspension holder for 50 tramways and railways comprising a cheek member provided with a threaded eye to permit the cheek member to be suspended, a 55 jaw member, a round fillet provided on said cheek member, a corresponding recess provided on the jaw member so that the jaw member may be slid on the fillet and be displaced longitudinally of the cheek member, cooperating recesses on said cheek and jaw members, and a removable split pin inserted in said last-mentioned recesses to prevent longitudinal displacement between the cheek and jaw members, the fillet on the cheek 60 member being laterally displaced therefrom so that the said split pin, the fillet and the trolley wire held by the holder are not in the same vertical plane.

AUGUST LINDE.
